RAIL ANCHOR SECURING MEANS

Max K. Ruppert, Chicago, Ill., assignor, by mesne assignments, to Poor & Company, Chicago, Ill., a corporation of Delaware

Application July 3, 1948, Serial No. 37,021

3 Claims. (Cl. 238—321)

1

This invention relates to an improved means for securing, to a railroad cross-tie, a rail anchoring device of the general class which has clamping engagement with the base portion of a railroad rail and abuts against a vertical face of the cross-tie to resist creeping movements of the rail in the direction of said abutment.

The creeping movement of a railroad rail results from a combination of several factors, including the vertical undulations or wave movements of the rail, which are produced by the rolling load on the rail as the car wheels pass across the spacing between adjacent ties. The pressures on the rail, tending to produce creeping movement thereof, is most pronounced in the direction of the moving load. Consequently, the said rail anchoring devices are positioned on the rail so that each anchoring device will abut against a vertical face of an adjacent cross-tie and thereby prevent forward creeping movements of the rail.

While the creeping pressure on a railroad rail is most pronounced in the direction of the traffic, each vertical undulation produces a retrograde pressure component which, unless it is adequately resisted, tends to move the rail in a direction to carry the rail anchoring device away from its abutting engagement with the cross-tie. Such condition removes the abutment resistance to the next forward creeping movement of the rail, whereby a substantially greater creeping pressure is built up by the unresisted movement of the rail.

A principal object of the invention is to provide a rail anchor securing device of inexpensive structure which will hold the anchor device firmly against an adjacent cross-tie, whereby the anchor will function to prevent both forward and retrograde creeping movements of the rail.

Another object of the invention is to provide a simplified structure which will function as a two-way anchor to prevent both forward and reverse creeping movements of a railroad rail and which will permit the rail clamping element, of the combination, to move vertically relative to the cross-tie. This capacity for relative vertical movement is important, since it prevents the vertical wave movement of the rail from pumping the cross-tie up and down in the ballast of the roadbed.

The two-way rail anchor structures heretofore proposed, and involving the provision of a rail clamp and a separate holding means for preventing retrograde movement of the rail clamp, have not been entirely satisfactory, since they

2

have usually involved attachments of the anchor holding member to a tie plate at a location whereby the creeping pressure on the rail tends to skew the tie plate out of its proper alignment with the rail. In some of the early proposals, for two-way rail anchors, the rail fastening spikes were utilized to secure the anchor holding member to the cross-tie, or to the rail. In either case, the retrograde creeping pressure on the rail is transmitted directly to the rail fastening spikes and thereby provide additional wear on the spikes.

The present invention, therefore, aims to provide a rail anchor securing means which avoids any attachment whatsoever to a tie plate and is connected directly to a cross-tie, whereby the tie plate, being relieved from all creeping pressure from the rail, will have no tendency to be skewed out of its proper alignment with the base portion of the rail.

It is also a principal object of the present invention to provide a two-way rail anchor structure of the above character which will permit the rail clamping member to be readily applied to and removed from the rail without disturbing the position of the rail, the tie plate, or the rail fastening spikes, and which will hold the rail clamp member firmly against the cross-tie without exerting disturbing pressures on the rail fastening devices.

The invention is illustrated, in a preferred embodiment, in the accompanying drawing wherein:

Fig. 1 is a plan view of a portion of a railroad rail and the underlying supporting structure together with a two-way rail anchor structure constructed in accordance with this invention.

Fig. 2 is a fragmentary face view of the structure shown in Fig. 1, and

Fig. 3 is a view of the structure shown in Fig. 2, looking toward an end of a rail clamping element.

The invention is illustrated herein in connection with a railroad rail and a conventional supporting structure for the rail.

The base portion of the railroad rail is designated by the reference numeral 10. It is seated on a tie plate 11 secured on the top face 12 of an ordinary wooden cross-tie 13. The tie plate is shown as provided with shoulders 14—14, at opposite sides of the rail, which provide lateral abutments for the rail and define the side limits of a rail seat 15. The tie plate 11 is formed with the usual spike openings 16 for receiving rail securing spikes 17. The tie plate may be secured to the top surface 12 of the cross-tie by means of additional spikes 18.

The rail securing spikes 17 are normally so

applied that a slight clearance is provided between the under-surface 19 of the spike head and the top surface of the rail base flange (see Fig. 2) so that the normal vertical wave movement of the rail will have no tendency to partially withdraw the rail fastening spike 17 from the cross-tie. Furthermore, the clearance between the bottom surface 19 of the rail spikes 17 and the base portion of the rail prevents the vertical wave motion of the rail from imparting vertical pumping movements to the cross-tie in the ballast of the roadbed.

Inasmuch as the rail fastening spikes 17-17 function to permit limited vertical movement of the rail relative to the rail supporting structure, but prevents abnormal relative movement, it is important, therefore, that the rail fastening spikes 17 be relieved, as much as possible, from lateral pressure tending to loosen them in the cross-tie. For this reason the present invention aims to avoid any direct attachment of the rail anchor device 20 to the tie plate 11.

The tie plate 11, as herein shown, has its edge 21 spaced inwardly from the vertical face 22 of the cross-tie, but this arrangement is merely for the purpose of accommodating the special form of rail anchor device 20 herein shown.

Inasmuch as the rail anchor securing means 23 of the present invention may be used in combination with rail anchor devices 20 of various forms and constructions, the specific form of rail anchor, herein shown, is used merely as an illustration and not as a limitation.

The said rail anchor device comprises a bar of substantially T-configuration, in cross-section, bent at one end into hook form to provide upper and lower jaws 24 and 25 for clamping the top and bottom surfaces, respectively, of one base flange of the railroad rail. The upper and lower jaws are driven into said clamping engagement by driving the anchor as a whole transversely of the rail. The other end of the anchor device is provided with a locking shoulder 26 which snaps up over the vertical edge 27 of the rail base, to hold the anchor device in its applied position. In the special form of anchor shown, the lateral flange 28 of the anchor device projects over the top surface 12 of the cross-tie; the vertical flange 29 being positioned to bear against the vertical face 22 of the cross-tie. This abutting engagement between the flange 29 of the rail anchor and the cross-tie, serves to transmit, directly to the cross-tie, all rail creeping pressures which are exerted in a direction to press the anchor device against the cross-tie.

It is known that, when a rail is subjected to creeping pressure in the direction of the moving traffic, for example, in a direction to press the anchor device against the vertical face 22 of the cross-tie, the abutting engagement between the said rail anchor and the cross-tie will prevent forward creeping movement of the rail. However, there is ordinarily no provision for resisting the reverse pressure component developed by the wave motion of the rail. Consequently, this reverse pressure component, unless resisted, tends to carry the rail anchor device away from its bearing contact against the vertical face of the cross-tie. Under such condition, the next forward creeping pressure on the rail is not resisted instantaneously. On the contrary, the rail moves forwardly before the anchor is again pressed against the adjacent cross-tie.

In order to overcome the said retrograde creeping action of the railroad rail and also provide a

5 simplified two-way anti-creeper for use in a single track having train traffic moving in both directions, the invention provides a simplified rail anchor securing means 23 in the form of a metallic strap. The said securing means is made from a flat metal bar, the ends 30-30 of which are bent at right angles to the middle portion 31. The said ends 30-30 are bent transversely of the greatest width of the bar so that the middle portion 31 thereof will bear edgewise against the depending flange 29 of the rail anchor device 20. The end portions 30-30 are provided with enlargements 32-32 which are pierced with suitable spike receiving openings and are rigidly secured to the top surface 12 of the cross-tie 13 by means of spikes 33. It will be observed in this connection that the said ends 30-30 of the anchor securing means are secured directly to the cross-tie as distinguished from the usual attachments to the tie plate, and thereby avoid transmitting rail creeping pressures to the tie plate or to the rail securing spikes 17. At the junctures of the ends 30-30 with the middle portion 31, the anchor strap is bent downwardly so that the mid-bent portions 35-35 of the said end portions flange 34 of the anchor device and engage the flange 29 of the anchor at a location below the top surface 12 of the cross-tie. The downwardly bent portions 33-35 of the said end portions 30-30 are preferably relatively short so as to prevent any substantial flexing of the anchor securing means when it is subjected to retrograde creeping pressure of the rail.

From the above it will be observed that the present invention provides a simplified two-way anchor comprising a rail clamping element and a means for firmly securing the rail clamping element to a cross-tie, but with capacity for vertical movement of the rail clamping element relative to the cross-tie and that the structure disclosed herein will also permit the rail anchor to be applied to and removed from the rail without disturbing the position of the rail, tie plate, rail securing spikes, or the rail clamp securing means.

I claim:

1. In combination with a railroad rail and an underlying cross-tie on which the rail is supported, of means for resisting longitudinal creeping movements of the rail in both forward and reverse directions comprising a rail clamping element adapted to be driven transversely of a rail to its applied position on the base portion of the rail and including a portion which extends across the rail beneath the base portion thereof and bears against a vertical face of the cross-tie to resist creeping movement of the rail in one direction, and a securing device secured directly to the cross-tie at locations spaced from the rail at opposite sides thereof and positioned to slidably engage one side face only of said rail clamping element to hold the opposite side face thereof in close contact with said vertical face of the cross-tie; the said securing device comprising a flat metal bar having its ends bent at right angles to the middle portion of the bar to provide arms for attachment to the cross-tie and the said middle portion is arranged to bear edgewise against the rail clamping element for the full length of the under-rail portion thereof and cooperates with the cross-tie to define a space for receiving said clamping element, which space is substantially longer than the clamping element so that the latter may be applied and removed from the rail without disturbing the position of the rail.
2. In combination with a railroad rail and an

underlying cross-tie on which the rail is supported, of means for resisting longitudinal creeping movements of the rail in both forward and reverse directions comprising a rail clamping element secured to the base portion of the rail and including a portion which extends across the rail beneath said base portion for bearing against a vertical face of the cross-tie to resist creeping movement of the rail in one direction, and a securing device secured directly to the top surface of the cross-tie at locations spaced from the rail at opposite sides thereof and positioned to slidably engage one side face only of said rail clamping element to hold the opposite side face thereof in close contact with said vertical face of the cross-tie; the said securing device comprising a flat metal bar having its ends bent at right angles to its middle portion to provide attaching arms for overlying the top face of the cross-tie and the arms being offset downwardly adjacent their junction with the said middle portion so as to position the said middle portion at a location spaced downwardly from the top surface of the cross-tie and spaced outwardly from the adjacent vertical face thereof, whereby said rail clamping device may be positioned in the space between the cross-tie and the said middle portion of said securing device and be thereafter driven transversely of the rail to its applied position thereon.

against a vertical face of the cross-tie to resist creeping movement of the rail in one direction, and a securing device secured directly to the cross-tie at locations spaced from the rail at opposite sides thereof and positioned to slidably engage one side face only of said rail clamping element to hold the opposite side face thereof in close contact with said vertical face of the cross-tie; the said securing device comprising a flat metal bar having its ends bent at right angles to its middle portion to provide attaching arms for overlying the top face of the cross-tie and the arms being offset downwardly adjacent their junction with the said middle portion so as to position the said middle portion at a location spaced downwardly from the top surface of the cross-tie and spaced outwardly from the adjacent vertical face thereof, whereby said rail clamping device may be positioned in the space between the cross-tie and the said middle portion of said securing device and be thereafter driven transversely of the rail to its applied position thereon.
